UNITED STATES PATENT OFFICE.

EMIL J. F. QUIRIN, OF TIOGA CENTER, NEW YORK.

LEAK-ALARM FOR PNEUMATIC TIRES.

983,837.

Specification of Letters Patent.

Patented Feb. 7, 1911.

Application filed January 29, 1910. Serial No. 540,888.

To all whom it may concern:

Be it known that I, EMIL J. F. QUIRIN, a citizen of the United States, resident of Tioga Center, in the county of Tioga and State of New York, have made a certain 5 new and useful Invention in Leak-Alarms for Pneumatic Tires; and I declare the following to be a full, clear, and exact description of the same, such as will enable others skilled in the art to which it appertains to 10 make and use the invention, reference being had to the accompanying drawings, and to letters or figures of reference marked thereon, which form a part of this specification.

Figure 1 is a longitudinal central section of my invention as applied with the valve closed. Fig. 2 is a similar view with parts broken away and showing the valve open to sound the whistle. Fig. 3 is a similar 15 view with escape of air stopped.

The invention relates to an alarm device for application to pneumatic tires of automobiles or motorcycles, serving to give notice when a serious leakage occurs in order 20 that the car may be stopped before it is caused to be deflected in its course by a deflated tire, which may result in serious loss of life or limb and damage to the car.

The invention consists in the novel construction and combinations of parts as hereinafter set forth.

In the accompanying drawings, illustrating the invention, the letter *a*, designates a spring controlled plunger valve in a nipple *b*, having communication with the air chamber of the tire *c*, said valve being normally held closed by the pressure of air in the tire, and the tension of its spring *a*², surrounding 35 an inner rod extension *c*², of the valve and located between the valve and a cup piece *c*³, having engagement with an inner shoulder *c*⁴, of said nipple, said cup piece being provided with lateral perforations *c*⁵. The inner rod extension *c*², of the valve has 40 slideable engagement with a central perforation *c*⁶, of said cup piece.

d, is an attachment tube having detachable screw-threaded engagement *d*¹, with the nipple *b*, and containing a spring-pressed 45 plunger *e*, having a bearing at *e*¹, against an outward rod extension *a*¹, of the valve *a*, an adjustment screw *f*, having screw-threaded engagement with the head *f*¹, of the tube *d*, having a bearing through its head *f*¹, 50 against the spring *g*, of the plunger *e*, whereby upon adjustment of said screw *f*, the

coiled spring *g*, will have its tension adjusted and be caused to press with greater or less force against the plunger *e*, and valve *a*. Thus when the tire is pumped up to the 55 point where it is desired the alarm shall sound, say forty pounds pressure to the square inch, and the screw *f*, is adjusted until the valve *a*, is pressed backward against the tension of its spring *a*², to open 60 position as shown in Fig. 2 of the drawings, air will be admitted through the lateral perforations of the cup piece past the valve into the cylinder or tube *d*, around the plunger, and will find an exit through a lateral 65 opening *d*², communicating with a right-angle whistle extension *h*, of said tube to sound the whistle. The tube or cylinder *d*, with the plunger *e*, and whistle extension carried thereby, are now unscrewed from 70 the nipple *b*, and the tire pumped up to 75 normal pressure, say 80 pounds to the square inch, when the tube *d*, and parts carried thereby are screwed in place again upon the neck *b*, the pressure of the spring *g*, as previously adjusted in the manner stated, being 80 now insufficient to overcome the increased air pressure against the valve *a*, which will remain closed until a leak occurs in the tire and the pressure therein is reduced to forty 85 pounds, when the alarm will sound as before stated.

j, indicates a jam nut for the adjusting screw, whereby when the regulation of the tension of the spring is made this regulation 90 may be fixed against casual disarrangement.

As shown in Fig. 3 of the drawings, after the whistle has sounded for a sufficient length of time to alarm the chauffeur of the motor car, the plunger *e* will take a 95 bearing against the screw-threaded end of the nipple *b*, to stop further unnecessary escape of air from the tire in sounding the whistle.

Having thus described my invention, what 100 I claim as new and desire to secure by Letters Patent is:

1. The combination with an inflation valve of a pneumatic tire having a nipple and a tension spring for holding the valve 105 normally closed, of a tube having detachable connection with said nipple, a plunger working in said tube and having operative engagement with said valve, and a tension spring for said plunger capable of overcoming the tension of the spring of said valve 110 to automatically open the same when pres-

sure in the tire is reduced beyond a predetermined point, said tube having an air escape opening and an alarm device in communication with said opening.

5 2. The combination with an inflation valve of a pneumatic tire consisting of a perforated nipple, a perforated valve seat in said nipple, a normally closed valve having engagement with said valve seat and 10 provided with a rod extension, and a tension spring for said valve, of a tube having detachable connection with said nipple, a plunger working in said tube, and a tension spring for said plunger pressing the plunger 15 against said rod extension and capable of overcoming the tension of the spring of said valve to open the same when pressure in the tire is reduced beyond a predetermined point, said tube having an air escape opening and an alarm device in communication 20 with said opening.

3. The combination with an inflation valve of a pneumatic tire consisting of a perforated nipple having an inner shoulder and 25 an outer perforated valve seat, a cup having engagement with said shoulder and pro-

vided with lateral perforations, a normally closed valve having engagement with said seat and provided at one end thereof with an outer rod extension having slideable engagement with said cup, and at the opposite end thereof an inner rod extension and a tension spring located between said cup and valve, of a tube having detachable connection with said nipple, a plunger working in 30 said tube, and a tension spring for said plunger pressing the plunger against said inner rod extension and capable of overcoming the tension of the spring of said valve when pressure in the tire is reduced 35 beyond a predetermined point, said tube having an air escape opening and an alarm device in communication with said opening, and means for adjusting the tension of the 40 spring of said plunger.

45 In testimony whereof I affix my signature, in presence of two witnesses.

EMIL J. F. QUIRIN.
